UNITED STATES PATENT OFFICE.

AIME BELLERIVE, OF ST. ELIZABETH, MANITOBA, CANADA.

GRAIN-DRILL.

No. 909,137.

Specification of Letters Patent.

Patented Jan. 12, 1909.

Application filed November 13, 1907. Serial No. 401,984.

To all whom it may concern:

Be it known that I, AIME BELLERIVE, a subject of the King of England, residing at St. Elizabeth, in the Province of Manitoba, Dominion of Canada, have invented certain new and useful Improvements in Grain-Drills; and I do hereby declare the following to be a full, clear, and exact description of the invention, such as will 10 enable others skilled in the art to which it appertains to make and use the same.

The present invention has reference to grain drills and it aims generally, to provide an exceedingly simple inexpensive and 15 effective machine of that class including a yieldingly mounted colter wheel, a boot disposed in the rear thereof, and a furrow coverer yieldingly connected to the boot.

With the above and other ends in view, 20 the invention consists in the particular construction, combination and arrangement of parts, all as hereinafter fully described, specifically claimed and illustrated in the accompanying drawings, in which like parts 25 are designated by corresponding reference numerals throughout the several views.

Of the said drawings: Figure 1 is a fragmental side elevation of a grain drill constructed in accordance with the present invention. Fig. 2 is a horizontal section on the line 2—2 thereof. Fig. 3 is a rear elevation of the boot. Fig. 4 is a horizontal section through the colter wheel and the boot, parts being removed. Fig. 5 is a perspective view of the furrow coverer.

Referring more particularly to the drawings, 5 designates the rearwardly-extending trail-bar which is pivoted at its forward end to the frame beam 6 of the drill and is 40 further connected therewith by an expandable coil spring 7, which embraces a rod 8 secured at one end to said bar and having its other end extending through an opening 9 formed in said beam. Towards its rear 45 end, the trail-bar is bifurcated as shown in Fig. 2 and is provided at such point with a colter wheel 11 rotatably mounted upon a journal pin 10 extending across the bifurcation. The colter is thus held yieldingly

against the surface of the ground by the 50 tension of the spring 7 as will be understood. The colter is of the ordinary construction and its beveled edges are cleaned by a pair of forwardly-extending scrapers 12 which are secured at their rear ends to 55 the heel portion of a boot 13, on opposite sides thereof, said scrapers being held against the colter by means of a pair of curved springs 17, disposed upon opposite sides of the trail-bar. The lower end of 60 each spring is secured to the adjacent scraper, while the upper end thereof is attached to the adjacent end of a pin 18, which passes through a horizontal opening formed in the rear end of the trail-bar. The boot is provided with a forwardly-projecting lug 19 which fits between the free ends of the arms formed by the bifurcation above referred to, the pin 18 passing through said arm ends and through 65 the lug, so as to effect a pivotal connection of the boot with the trail-bar. The rear face of the boot has secured thereto the shorter arm of an inverted V-shaped bracket 14, to the free end of which arm is 70 hinged a covering plate 15. This plate is held yieldingly in position by an expandable coil spring 16, which is interposed between said plate and the other arm of said bracket and embraces a pin 20 which is formed upon 75 or secured to the plate 15, said pin extending through a perforation formed in the last mentioned arm of said bracket.

From the foregoing description, it will be apparent that the seed will be fed from 80 the boot into the furrows drilled by the colter, the furrows being subsequently closed by the coverer.

What is claimed is:

The combination, with a frame, of a rearwardly-extending trail-bar pivoted at its forward end to said frame and provided at its rear end with a bifurcation; a journal pin extending across said bifurcation; a colter rotatably mounted upon said pin; a boot pivotally connected with the rear end of said trail-bar; a pair of scrapers secured to the heel of said boot and bearing against

opposite sides of said colter; a spring disposed upon each side of the trail-bar and connected with the adjacent scraper for holding the same in place against the colter; an inverted V-shaped bracket having one arm thereof secured to the rear face of said boot; a covering plate hinged to the free end of said arm; and a spring interposed between

the other arm of said bracket and said plate, for yieldingly holding the latter in position. 10

In testimony whereof, I affix my signature, in presence of two witnesses.

AIME BELLERIVE.
